Application May 20, 1944, Serial No. 536,584

4 Claims. (Cl. 250—17)

1

My invention relates broadly to remote control systems and more particularly to a system for transmitting warning signals in remote control systems.

This application is a continuation in part of my application Serial No. 373,173, filed January 4, 1941, now Patent 2,355,055, issued August 8, 1944, for Electric relay system.

One of the objects of my invention is to provide an electric relay system for operation in a remote control system by which various circuit permutations and combinations may be effected and in addition a repeating warning signal may be controlled by the relay system.

Another object of my invention is to provide a local and remote control circuit for a radio transmission system by which the radio transmitter may be operated from a remotely controlled location for transmitting a warning signal preceding a radio transmission by voice modulation or other means.

Still another object of my invention is to provide a remote control system for radio signaling systems whereby composite signals may be transmitted over desired time sequences by a radio transmitter that is remotely controlled from a supervisor position.

A further object of my invention is to provide a control circuit for a remote control system capable of establishing three different circuit conditions over a control line by displacement of a control key or switch to either of three selective positions.

Other and further objects of my invention reside in an arrangement of electric relay system having means for controlling the operate and release time of the magnetic system of a relay system as set forth more fully in the specification hereinafter following by reference to the accompanying drawings, in which:

Figure 1 is a schematic wiring diagram showing the remote control system of my invention for distant control of a radio transmitter whereby a warning signal may be transmitted from the radio transmitter to signify the commencement of a broadcast followed by the desired broadcast in desired sequence; Fig. 2 schematically illustrates the circuit condition at the controlling station when the control key or switch is manually held in dial position; Fig. 3 schematically illustrates the circuit condition when the control switch or key is moved to locking ring position; Fig. 4 schematically shows the circuit condition when the control switch or key is in locking neutral position; Fig. 5 shows a characteristic curve for the electric relay system used in the remote control system of my invention in which the electrical operating time of the relay system is regulated in accordance with the principles of my invention; and Fig. 6 shows a characteristic curve in which both the electrical and mechanical char-

2

acteristics of the relay system are controlled for securing the repeat signal operation required as a warning signal in the remote control system of my invention.

5 My invention provides a method of remote control for a radio broadcast transmitter or other signalling system for transmitting a warning signal in advance of a broadcast. The system of my invention is particularly applicable in aircraft traffic control and navigation systems in which an operator in a remote position with respect to a transmitting ground station desires to notify aircraft that a broadcast is about to commence. The operator in the remote control station is provided with a three position switch or key having a manually actuated dial position, a locking ring position and a locking neutral position. The operator may manually move the control switch to dial position and dial a particular digit on the 10 remote control mechanism at the control station and then quickly shift the control switch or key to ring position and allow the switch or key to remain locked in ring position and in accordance with the system of my invention effect the transmission of warning signals at a rate of 15 approximately eight per second on any selected audio tone frequency such as 1,020 cycles. The warning signals at 1,020 cycles are transmitted so long as the control operator allows the control 20 key or switch to remain in ring position, thereby advising the pilots of aircraft that a broadcast is about to commence. The operator may then shift the key or switch to neutral locking position 25 and control the modulation circuit of the distant radio transmitter either by voice or telegraph signals. The control switch or key is always 30 ready for a repeat control operation, the important sequence being the movement of the control switch or key first to dial position for effecting 35 a selection of the connection between the warning circuit and the modulation circuit of the radio transmitter. Such selection when once established is not disturbed by quick movement of the control key or switch to ring position because of the time relay characteristics of the 40 relay circuits employed between the control circuit and the selector apparatus and the almost infinitesimal interruption of the control current. This method of transmission has proven highly 45 effective in the transmission of weather, emergency warnings, traffic, and other information to aircraft in a particular area. However, my invention is not limited to this particular application and is applicable to signalling systems generally in which a calling signal of predetermined 50 characteristic is to be transmitted in advance of the signalling operation. My invention also has application to the transmission of signals of particular tones for controlling of start-stop functions for the motor circuits of facsimile and 55 printing telegraph systems and for the starting 60 of the motor circuits of facsimile and printing telegraph systems and for the starting

and stopping of the auxiliary control circuits of television equipment by remote control.

Referring to the drawings in detail, I have illustrated a remote control system of general application in which in Fig. 1 the equipment at the remote control station is designated generally at 11 while the equipment at the transmitting station is indicated generally by reference character 12 with the line system 13 interconnecting the stations. An alternating current supply circuit has been illustrated generally at 14 coupled through audio frequency transformer 15 to the contacts of the control key 18 for controlling connections to the line system 13. The control key 18 is indicated generally as having a dial position 19 and a ringing position 20. The dial switch control device at the remote control station is indicated at 16. The signalling circuit is indicated at 17 having leads L1 and L2 normally connected through key 18 to the line 13. The operator at the remote control station by moving key 18 to the dial position 19 and operating the dial 16 opens and closes the circuit over line 13 for transmitting impulses to the controlled station. At the controlled station relay A-4196 follows these impulses and through its back contact 1 causes the motor magnet 10 through intermediate relay B-4196 to actuate the stepping switch 21-22 the specific number of steps corresponding to the impulses transmitted from the dial through any suitable range such as 1', 2' . . . 30'. Relay B-4196 and a cut-out relay D-4196 are both of a slow release type. The reason for the use of time delay feature in the circuit of my invention is to prevent opening of the contacts in the absence of a control current for a given time period for maintaining the circuit in operation. The infinitesimal interruption of current from source 14 in the control circuit upon movement of key 18 from dial position 19 to ring position 20 does not interfere with the maintenance of the selection circuit because of the slow release action of relay B-4196. The intermediate relay B-4196 due to its slow release action remains operated after its circuit is first closed, thus holding its contacts 2-3 closed. After the last impulse from the dial, relay D-4196, which operated on the first impulse from relay A-4196, due to its slow release action remains operated during the series of impulses transmitted from the dial and restores and closes a circuit from positive on contact 2 of relay A-4196 to the primary relay associated with the last stepping relay step. Relay A-4196 remains energized so long as key 18 remains in dial position after the series of impulses has been transmitted, in order to maintain the selected primary relay energized, or so long as key 18 remains locked in ring position for transmitting current from source 14 to the line circuit. The dial position of the control circuit is shown more clearly in Fig. 2 while the ring position of the control circuit is shown more clearly in Fig. 3.

The neutral position for key 18 is shown in Fig. 4. Key 18 is of the cam lever type in which the movement of the lever to which handle of key 18 is attached functions to engage cam members connected with the leaf springs for moving the leaf springs to operating position.

In Fig. 2, for example, wherein the key lever is moved to dial position the lever arm connected with the operating handle of key 18 engages cams associated with lever springs 66 and 67 which are connected to the line circuit 13 serving to spread the leaf springs and move them to positions in

which they establish connection with contacts 68 and 69 as shown. This completes a circuit from line 13 through leaf spring 67 on contact 69 to winding 15 of the transformer circuit and through dial switch 16 and resistance 70 to contact 68 and leaf spring 66 returning to the opposite side of line 13. Leaf spring 66 is associated with pedestal insulator 71 which connects with leaf spring 72 for simultaneously moving leaf spring 72. Leaf spring 72 when shifted as shown in Fig. 2 establishes connection with contact 73 which places warning lamp 74 in circuit with the power supply source from winding 15 of the transformer circuit 14 thereby indicating to the station operator that key 18 is in dial position.

In the position illustrated in Fig. 3 wherein the lever controlled by switch handle 18 is moved to ring position, it will be observed that leaf springs 68 and 67 have been restored to neutral position and establish connection with contacts 74 and 75 respectively completing circuits to the lever springs indicated at 76 and 77. The movement of key 18 to the position illustrated in Fig. 3 results in displacement of spring members 76 and 77 to positions establishing connection with contacts 78 and 79 in circuit with winding 15 of transformer circuit 14. This results in transmitting current from source 14 to line 13 so long as key 18 remains in the position illustrated in Fig. 3.

When key 18 is restored to neutral position as illustrated in Fig. 4 leaf springs 76 and 77 establish connection with contacts 80 and 81 connected to the supervising line circuit through leads L1 and L2 thereby establishing connection with a signalling circuit or a modulating circuit at the radio transmitter indicated at 28.

Delayed action relay B-4196 prevents any interference with the proper functioning of the control system by prolonging the circuit continuity during transition produced preparatory to control of the system by current impulses transmitted from the control station.

The primary relay operates to close a circuit 45 to the desired control which is required. This control may be the closing of certain amplifier circuits or other desired switching operations. In the particular system illustrated, I have shown the broadcast transmitter as comprising a modulation system 29, an oscillator 31, a power amplifier 32 and an antenna-ground system 33. A modulation control circuit 28 extends to the modulator 29 and a local microphone 34 is provided in this circuit for any local control which 55 may be required. An audio frequency transformer 27 has its secondary winding connected to modulation circuit 28 and its primary winding connected to the leaf springs 25 and 26 of the spring pile-up 24 of the auxiliary relay 39. The 60 contact springs 25 and 26 move to either of two positions. In the upper position, contact springs 25 and 26 connect with contacts 35 and 36 which connect to the contacts 4 and 6 of the contact assembly 23 of relay B-4196. In the opposite position, leaf springs 25 and 26 connect respectively with contacts 37 and 38 leading to the tone frequency source under control of the relay system 42 of my invention. The relay 42 comprises the magnetic core 44, the operating winding 43, the 70 slow operate slug 45 for electrically controlling the operating time of the relay and the armature 46 pivoted at 47. The armature 46 has an operating lever arm 49 integral therewith which controls the operation of the spring pile-up shown at 75 50. The armature 46 has the inertia device 48 at-

tached thereto for mechanically controlling the operating time of the relay. The spring pile-up 50 includes leaf springs 51, 52, 53, 54, 55 and 56. The leaf springs 51—52 carry contacts 51a and 52a which are electrically connected in series with the control winding 43 and with the power source through contact spring 40 and coacting contact 41 of auxiliary relay 39. The relay 42 is thus self-interrupting through the cooperation of contacts 51a and 52a in the current path to the relay winding 43 at a rate of time depending upon the coaction of the inertia of armature 46 due to the added mass 48 and the influence of the eddy current field produced by slug 45 upon the normal field of winding 43.

A suitable source of alternating current having a tone frequency, for example, of 1020 cycles is connected at 57 to primary winding 58 of transformer 59, whose secondary winding 60 is connected to leaf springs 54 and 56 of spring pile-up 50. The movable contact springs 52, 53 and 55 are interconnected through bushings of insulation material indicated at 61 and 62 so that movement of lever arm 49 moves leaf spring 52 to open contacts 51a and 52a while leaf springs 53 and 55 move to positions in which contacts 53a and 55a establish connection with contacts 54a and 56a, respectively, thus closing the circuit from secondary winding 60 of transformer 59 to the contacts 37 and 38 of spring pile-up 24 of auxiliary relay 39. I have schematically illustrated the primary relays of the remote control system at E—4196 and F—4196 and the secondary relays at G—4193. I have schematically shown the several contacts and leaf springs for the several relays and control apparatus at 1, 2, 3, 4, 5, 6, 7, 8 and 9 with polarities indicated to aid in tracing the circuits of the control system.

In the instant case assume that it is desired to broadcast a certain message. The operator moves key 18 to dial position 19 and dials the digit 3 which causes the stepping switch 21—22 to step to its third contacts and relay A—4193 to remain energized afterward. Relay D—4196 on restoring after the third impulse closes a circuit to primary relay 3. Primary relay 3 closes a circuit to the auxiliary relay 39 which transfers the circuit from contacts 23 leading to the modulation channel through the primary of the broadcast transformer 27 to contacts 54 and 56 on the weighted armature relay 42 of my invention. The circuit to the winding 43 of the weighted armature relay 42 is also closed by the auxiliary relay 39 through spring 40 and contact 41 and as previously described, the weighted armature relay 42 operates approximately eight times per second to cause a warning 1020 cycle tone to be placed on the modulation circuit 28 of the broadcast station. This interrupted tone is held on the modulation circuit of the broadcast station as long as the operator at the distant control station allows the key 18 to remain locked in ring position as shown in Fig. 3. After this tone has been held on the desired length of time for transmitting the warning signal the operator restores the key 18 to neutral position as shown more clearly in Fig. 4, and the stepping switch 21—22 restores itself to normal.

The control operator by using key 18 and dial 16 as before, then dials the broadcast number and the stepping switch 21—22 functions to operate the primary and secondary relays to effect whatever functions they control, with leaf springs 25—26 of spring pile-up 24 contacting the contacts 35 and 36 as shown in Fig. 1, after which

key 18 is restored to neutral as shown in Fig. 4 and the broadcast takes place. Thus a multiplicity of functions may be controlled over the same line circuit by selection through the stepping switch mechanism 21—22. After the warning signals have been transmitted as hereinbefore explained the operator upon moving key 18 to neutral in effect places signaling circuit 17 in supervisory position through leads L1 and L2 to line 13 and through contacts 4—5 and 6—7 and contacts 24—25 and 36—26 to the modulation transformer 27 of the modulation circuit 28 of the radio transmitter. Thus a microphone and power source connected to signaling circuit 17 enables the radio transmitter to be voice modulated from the remote control position. If a sending key and power source is connected to signaling circuit 17 or any other form of modulating means employed the modulation circuit 28 of the radio transmitter can be correspondingly controlled.

I have found the relay system of my invention very practical and successful in operation. The mass added by weight 48 provides the movable armature system with that amount of mechanical inertia which will coact with the electrical influence introduced by slug 45 to enable operating winding 43 while energized from a continuously applied source to cause the controlled circuit connected through sets of contact springs 53, 54, 55 and 56 to alternately connect and disconnect a source of control potential to the circuit to be controlled. The rate at which this control is applied is readily controllable by changing the character of slug 45 and the effective mass 48.

Figs. 5 and 6 illustrate the effect of the slug 45 and the weight 48 on the movable armature. In Fig. 5 the curves illustrate the manner in which the flux density increases and decreases in the magnetic system according to time where the flux builds up during the make period of contacts 51a and 52a and decreases to a condition where it commences to increase again before the flux cycle through the magnetic parts has been completed. The influence of slug 45 in the example illustrated is such that the flux cycle increases through a time period represented by a unit of time while the decrease in flux takes place over a fourth of the increase time. The self-interruption effected by the breaking of the circuit through winding 43 by contacts 51a and 52a produces a repetition of alternate increases and decreases of the flux cycle as illustrated. In order to increase the rate of make and break of the spring pile-up system the mass 48 is added to armature 46 with the result shown in Fig. 6. The time period for initial build-up of the magnetic flux is now one unit of time compared to a tenth of the time for decrease of flux. The flux cycle is not completed but repeats in a series of substantially saw-tooth curves as indicated until the controlling current is removed. During this period the spring pile-up assembly is being functioned through a series of rapid repeating strokes and impresses the characteristic tone frequency from source 57 upon the load circuit or modulation circuit of the radio transmitter illustrated in Fig. 1. By proportioning the mass of the movable armature system and the arrangement of slug 45 in the field of winding 43 a rate of make and break of, for example, eight times per second may be obtained.

The composite system of control of my invention enables an operator at the remote control

station 11 to control the operation of the radio transmitter at the local control station 12 so that voice transmission from the radio transmitter may be preceded by a warning signal produced by operation of the recycling relay system which may be controlled sequentially to connect the 1020 cycle tone to the modulation circuit of the transmitter through transformer system 27. The modulation circuit of the transmitter may be controlled by the supervisor from the remote control station for emitting the desired characteristic of signal and the radio transmitter may also be locally controlled through microphone 34 connected with the voice modulation circuit 28. The slow release relay B-4196 in the control system prevents opening of relay contacts in the absence of a controlled current for a given time period, thereby maintaining the system in operation. The interruption of the key control circuit 18 does not interfere with the maintenance of a selector circuit because of the slow release action of relay B-4196.

I realize that various changes may be made in the relay arrangement and while I have described my invention in certain preferred embodiments, I desire that it be understood that modifications may be made and I intend no limitation upon my invention other than may be imposed by the scope of the appended claims.

What I claim as new and desire to secure by Letters Patent of the United States is as follows:

1. A control system for a signal transmission system comprising a transmitting station including a signal transmission system having a local voice modulation circuit, an audio frequency energy transmission channel connected with said local voice modulation circuit, a source of alternating current, a mechanically recycling relay including an operating winding, a movable armature and a multiplicity of contacts controlled thereby, circuits interconnecting said source of alternating current and certain of said contacts, a remote control station including an alternating current control source, a two-position control switch and a dialing switch, a circuit interconnecting said control source, said dialing switch and one position of said two-position control switch, a signalling circuit connected with the other position of said two-position control switch, a line wire control circuit interconnecting said remote control station and said signal transmission system for selectively establishing connection between said first mentioned source of alternating current and said audio frequency energy transmission channel and controlling the impression of said first mentioned source of alternating current upon said audio frequency transmission channel at a rate determined by the operation of said mechanically recycling relay for correspondingly controlling the emission of a sustained signal from said signal transmission system through said local voice modulation circuit.

2. A control system for a signal transmission system comprising a transmitting station including a signal transmission system having a local voice modulation circuit, an audio frequency energy transmission channel connected with said local voice modulation circuit, a source of alternating current, a mechanically recycling relay including an operating winding, a movable armature and a multiplicity of contacts controlled thereby, circuits interconnecting said source of alternating current and certain of said contacts, a remote control station including an alternating

current control source, a two-position control switch and a dialing switch, a circuit interconnecting said control source, said dialing switch and one position of said two-position control switch, a signalling circuit connected with the other position of said two-position control switch, a line wire control circuit interconnecting said remote control station and said signal transmission system for selectively establishing connection between said first mentioned source of alternating current and said audio frequency energy transmission channel and controlling the impression of said first mentioned source of alternating current upon said audio frequency transmission channel at a rate determined by the operation of said mechanically recycling relay for correspondingly controlling the emission of a sustained signal from said signal transmission system through said local voice modulation circuit, and means connected with said line wire control circuit for delaying the opening of said circuit in the absence of a controlled current.

3. A remote control system comprising in combination a remote control station and a local control station, a line wire circuit interconnecting said stations, a controlling source at said remote control station, a signal transmitter at said local control station, a mechanically recycling relay at said local control station, a source of alternating current connected with said mechanically recycling relay, a voice modulation circuit connected with said signal transmitter, and means operated from said remote control station for directly controlling said voice modulation circuit of said signal transmitter or conditioning said mechanically recycling relay for periodically impressing the source of alternating current at said local control station upon the voice modulation circuit of said signal transmitter over a predetermined time interval.

4. A remote control system comprising a transmitting station including a signal transmission system having a local voice modulation circuit, an audio frequency energy transmission channel connected with said local voice modulation circuit, a mechanically recycling relay including an operating winding, a movable armature and a multiplicity of contacts controlled thereby, a tone frequency source connected with said multiplicity of contacts, means for completing a circuit between said local voice modulation circuit or between said local voice modulation circuit and said audio frequency energy transmission channel, a control station, an audio frequency source and a signal circuit at said control station, and a selector switch at said control station for rendering either said signalling circuit or said audio frequency source at said control station effective over said audio frequency energy transmission channel for selectively controlling the connection of said mechanically recycling relay or said audio frequency energy transmission channel to said local voice modulation circuit.
